UNITED STATES PATENT OFFICE.

MAURITZ C. INDAHL, OF PHILADELPHIA, PENNSYLVANIA, ASSIGNOR TO LANSTON MONOTYPE MACHINE COMPANY, OF PHILADELPHIA, PENNSYLVANIA, A CORPORATION OF VIRGINIA.

TYPOGRAPHIC CASTING AND COMPOSING MACHINE.

Application filed November 29, 1922. Serial No. 604,069.

To all whom it may concern:

Be it known that I, MAURITZ C. INDAHL, a citizen of the United States, and a resident of Philadelphia, county of Philadelphia, State of Pennsylvania, have invented certain new and useful improvements in Typographic Casting and Composing Machines; and I do hereby declare the following to be a full, clear, and exact description 10 of the same, reference being had to the accompanying drawings, forming part of this specification, and to the characters of reference marked theron.

This invention relates to typographic 15 casting and composing machines adapted to operate in accordance with signals such as those in the form of perforations in a controller strip. A machine of the kind referred to is exemplified in the commercial 20 product of Lanston Monotype Machine Company, and its basic principles are well-known and are shown, for example, in United States Letters Patent No. 625,998 dated May 30, 1899. The record strip itself 25 may be produced in any suitable manner but is preferably the product of a keyboard machine such as that, for example, illustrated in United States Letters Patent No. 944,405 dated December 28, 1909, or an improved 30 form of such patented machine.

In the present commercial form of these machines the keyboard produces perforations of such nature as to act directly in the casting machine to throw up gage pins or 35 operate other mechanisms for controlling the casting machine in its operations of locating the matrix case and the wedges for controlling type body and space body sizes. It has been proposed, for example, in United 40 States patent application No. 582,238, filed August 16, 1922, to construct a keyboard mechanism by which controller strip signals of an indirect nature may be produced, namely, combination or additive signals in 45 which each perforation does not represent a definite gage or other mechanism to determine matrix case or wedge location, but indicates a definite value to which the values of the other perforations in the signal are 50 to be added in order to arrive at the meaning and effect of the signal as a whole.

An object of the present invention is to produce a machine for operation in accordance with, and under the control of, such

combination signals. Another object is to 55 provide a typographic casting and composing machine, such as that basically shown in Patent 625,998, above mentioned, with an interpreting mechanism whereby the usual matrix and wedge locating mechanism may 60 be actuated in accordance with such combination signals. Another object is to construct a machine having a plurality of motors or mechanisms to be actuated, such as pneumatically operated locational gages, 65 whereby such machine will operate under control of a record strip having signal indications the greatest possible number of which is less than the number of said motors or mechanisms. A more specific object is to 70 produce a machine of the kind referred to in which a strip having a relatively small signal indication capacity controls interpreting mechanism provided with bars having selectively positioned openings or the 75 like, which bars by combination as controlled by the signal components, open a single through way or passage for each combination to actuate a single motor such as the gage pins 150 hereinafter referred to; 80 thus each combination though possibly made up of a plurality of signal components or values, in the form, preferably, of perforations, produces by combining these values, a single effect; but the total number of sig- 85 nal perforations of which the strip is capable may be less in number than the motors, as 150, to be actuated.

Further objects and advantages will hereinafter be particularly pointed out or will 90 otherwise appear in connection with the following description of the embodiment of the invention illustrated in the accompanying drawings in which:

Fig. 1 is a side elevation of the air or 95 paper tower of a machine similar to that of Patent 625,998 previously referred to and embodying the present invention.

Fig. 2 is a longitudinal section on approximately line 2—2 of Fig. 3.

Fig. 3 is a vertical section on approximately line 3—3 of Fig. 2.

Fig. 4 is a vertical section on approximately line 4—4 of Fig. 2.

Fig. 5 is a horizontal section on approximately line 5—5 of Fig. 2.

Fig. 6 is a diagrammatic representation of the invention.

Fig. 7 is a horizontal section on approximately line 7—7 of Fig. 4, and

Fig. 8 is a perspective view of a portion of a modified signal interpreting mechanism.

The paper tower shown in the drawings will be recognized as a part of the patented machine above referred to, it being deemed unnecessary to show other portions of the machine because it is well-known to those skilled in the art. The well-known mechanical elements of the machine shown may be referred to briefly for identification purposes, for example, the top stand 1 of the machine, the paper tower base 2, the housing 3, the paper tower lever 4, the paper feed pawl ring 5, the air bar clamping lever 6, the locking lever 7, the winding spool 8, the paper feed operating rod 9, the bell crank lever 10 for operating the rod 9, the air bar lever 11, the paper feed ratchet 12, the cross girt or tracker bar 13, the pin wheels 14 provided with pins for engaging with marginal perforations in the controller strip for feeding the same, the air bar 15, the air valve 15'; and in Fig. 6 are shown diagrammatically the pin blocks B and C and their pin jaws and pneumatically operated gage pins or motors 150, as well as motors operated by air under pressure from the cross girt 13 to govern other gaging devices of the machine when it is to operate in accordance with justification space signals and justification signals, these motors being marked S for the justification space signal, J75 for the .0075 justification signal, and J5 for the .0005 justification signal, these signals being well understood in the art.

In accordance with the present invention, the cross girt 13 is made narrower to accommodate a narrow paper, and contains only eleven ports instead of the usual thirty-one. The piping is also altered and the paper tower is provided with an interpreting mechanism 16 secured at the back of the paper tower. This mechanism may be readily divided into two groups, one pertaining to the B pin block of the machine, and the other to the C pin block thereof. Each group embodies four permutating bars 17, each bar being operated, through the intermediary of its bell crank lever 18 pivoted to the paper tower housing, by its motor 19, each motor being connected with its appropriate port in the cross girt by one of the pipes 20. Each bar 17 is normally retained in a retracted position by a spring 21 connecting one end of the bell crank lever 18 with the piston block 22 in bores in which the motor pistons 19 are located. The motor pistons 19 are staggered as illustrated, (Fig. 5), and the bell cranks 18 have their horizontal arms laterally extended to reach directly under the pistons 19. Each bell crank lever 18 is provided with two lugs 23, one

of which in each case engages with its corresponding piston 19, and the other of which engages with the bottom of the piston block 22 to act as a stop against the pull of spring 21. The bars 17 are horizontally slidable in a slotted frame member 24 which rests upon the casing 25' secured to the base 2. One group consisting of four bars is in the front of and the other four-bar group behind a series of air valves 25 located in bores in the air block 26, which block is covered by a cover plate 27, the block and cover being secured to the casing 25' by screws 28. The valves 25 may be regarded as consisting of two groups, each group of fourteen valves 80 each, one group pertaining to the B pin block and the other group to the C pin block. The casing 25' is provided with screws 29, (Fig. 4), by which the casing is secured to the air tower base 2, and has screwed to its upper portion a slotted plate or frame 30 for the accommodation of valve operating members or fingers 31. These members have horizontal upper portions lying in the slots of the plate 30, and vertical descending portions for engagement with operating bar 32. The members 31 may also be considered as of two groups, fourteen in each group, each member being in contact along its rear edge with the corresponding member of the other group and their horizontal portions extending in opposite directions. It will be understood that the operation in an upward direction of any member 31 in the B group will open a corresponding valve 25 in said group, and that the operation of any member of the C group will likewise open a corresponding valve 25 of the C group, the valve stems being in line with the members 31 for this purpose.

The operating bar 32 is located in a cavity, one half of which is formed in the B group of members 31, and the other half in the C group. This bar is journaled at its ends to the forked ends of the lever 33 pivoted at 34 to the casing 25' and having its outer end provided with a cam engaging surface 35. The operating rod 36 is pivotally connected at its lower end 37' to the paper feed bell crank lever 10 previously referred to, its upper end being provided with a cam face 36' slidably held by a bracket 36'' secured to the casing 25' so that said cam face may engage with the surface 35 of the lever 33. On the upward movement of lever 10 the cam 36' will act, as is obvious, to move the lever 33 and the bar 32 to restore to their lowermost position, as shown in Fig. 4, the members 31. When this lever 10 moves downwardly in the usual manner to feed the controller strip, and after the latter has been clamped by the air bar 15 and the air has been allowed to traverse the signal perforations in the controller by the opening of the air valve 15', the cam face 130

36' of the rod 36 is moved downwardly sufficient to allow lever 33 to swing and the operating bar 32 to move upwardly due to the action of the plungers 37, one for each member 31, as shown in Fig. 7. It will be understood that the construction is such that the air in traversing signal perforations will operate motors 19 and permutating bars 17 before the members 31 are allowed to move upwardly. Such upward movement will result in one of the members 31, for each group, passing through a through way provided by the combination of permutating bars, in which case these members will open corresponding valves 25 and thus cause corresponding locational gages to be operated. These gages may be referred to as motors to be actuated and are shown in the form of air pins 150 in the pin blocks B and C to be operated. Likewise the cams 35 and 36' are so positioned and formed as to cause the retraction of the members 31 during the upward stroke of the lever 10 before a new signal has been presented which may result in the shifting into a new combination of the permutating bars 17.

The plungers 37 which act to operate the members 31 are provided for this purpose with stems 38 surrounded by coiled springs 39 (Fig. 4). These springs serve to move the plungers upwardly and consequently the corresponding members 31, there being a cavity 39' formed in the frame member 30 and shown in dotted lines in Fig. 4, to permit this upward movement of the plungers 37. It will be noted by an inspection of Fig. 7, that these plungers are staggered so as to take up as little room as possible.

Whether the two groups of members 31 are permitted to operate in an upward direction to open their corresponding valves, depends upon the permutating bars 17. It will be noted particularly in the diagrammatic representation shown in Fig. 6, that these various permutating bars are provided with slots or ways 50 in their lower edges, these slots being selectively arranged in the individual bars so that the operation or non-operation of any one or more of the bars will present aligned slots for permitting the upward movement of one of the valve operating members 31. In any combination of positions for the various permutating bars in each group, there will be only one through-way or passage provided by the alignment of slots in the various bars, this through-way permitting the thus selected operating member 31 to move through its operating distance in an upward direction and in so doing extend into the slots 50 and operate its corresponding valve 25.

In Fig. 6 the operation of the device, the construction of which has already been described, is diagrammatically shown, and it will be observed that the cross girt 13 is pro-

vided with eleven ports, the values or meaning of which are indicated from left to right as follows:—1, 2, 8, 4, S, .0075, 8, 2, 1, 4 and .0005. When a controller strip is threaded into the feeding apparatus of the paper tower, and the air bar 15 is clamped against it, air will pass from the bar 15 through whatever perforations are in the paper, it being noted particularly that the maximum number of perforations or of signal components is eleven instead of the usual thirty-one. If a perforation opposite the port S is opened, air will pass, as shown in Fig. 6, to the justification space motor S, and will operate this motor and cause the casting machine to perform so far as this particular perforation is concerned, in its usual manner; likewise if port .0075 or port .0005 is opened, air under pressure will cause the justification motors J75 or J5 respectively, to operate in the usual manner. The remaining ports may be divided into two groups having values 1, 2, 4 and 8; the left hand group leads to four motors 19 which control the group of permutating bars 17 for controlling the pins of the C block, while the right hand group of perforations controls similar motors and bars for the B block. The values of the various permutating bars of each group are numbered 1, 2, 4 and 8, and these bars correspond exactly to the values of the ports as already given. In the retracted position of the bars, as shown, there is no combination of slots which will allow a valve operating member 31 to move in such a way as to operate a valve 25. Consequently, this being a condition of no signal perforation whatever in the controller paper, the jaws of the B pin block and those of the C pin block will operate in the usual manner to come together at the particular end pin numbered B 15 and C 15 respectively, which pin is not connected to any air pipe, but is permanently attached to the pin block in raised position. The jaw nearest the permanent pin is constructed so that it will slide over this or any pneumatically operated pin without contact, the jaws being spring controlled so that the jaw farthest from the permanent pin, first moves to contact with the nearest operated pin or with the permanent pin if no other pin is operated, and thereafter the jaw nearest the permanent pin moves until it comes against the other, pin-located jaw. In the position of the jaws, as determined by the permanent pin, the matrix case will be brought to a position for casting a quad in accordance with the usual practice.

If, however, any perforation occurs as to the two groups of perforations having values, the correspondingly valued motors 19, bell crank levers 18 and permutating bars 17 will be operated to produce a combination of slots for permitting the operation of

a member 31 and its corresponding valve 25. When a valve 25 is operated by moving upwardly, air under constant pressure admitted above the valves through the pipe 40, (Fig. 4), enters the chamber 41 and passing the valve seat will flow through the outlet channel 42 from this valve and through the pipe of the group of pipes or conduits 43 connected thereto. The farther end of this pipe is connected with a pin in one of the pin blocks which corresponds with the selected valve. When an operated valve has again become seated air from the pipe 43 will exhaust around the reduced portion of the valve stem and through the passage 44 for that valve, there being such a passage for each valve provided in the valve block 26. It will be unnecessary to explain all of the possible combinations that may be obtained, although it may be pointed out that with four perforations in each group it is possible to operate any one of fourteen valves 25, and therefore, any one of the fourteen air pins in the pin blocks B and C. Let us however take one example for explanatory purposes—suppose air is allowed to pass through the ports 4 of the left hand group and 8 of the right hand group; the air passing through port 4 will operate a motor 19 and its corresponding permutating bar 17 of the C group, this bar being marked with the value 4 corresponding with the value of the port (Fig. 6.) This bar in operating will move until its stop 17" comes against the casing 25' in which case the operation of this bar and the non-operation of the other bars will produce a combination of slots in which a through-way is opened to the fourth member 31 from the left in the C group, thus the fourth valve 25 will be operated and the fourth pin of the C block. Similarly, air entering the perforation in the right hand group, the value of which is 8, will operate the bar in the B group which has the value of 8, and this will cause a through-way to be formed by the combination of slots, for the eighth operating member 31 from the left and correspondingly the eighth valve and the eighth pin in the pin block B. It will be seen that the pin corresponding in value to the port value indicated, is operated when that particular port is opened. When, however, more than one port is opened, as let us say, ports 8 and 1 in one group, the permutating bars, the values of which are 8 and 1, will be operated, in which case, as will be clearly seen by an inspection of Fig. 6, the ninth valve will be operated and the ninth air pin; thus each variety of combination could be explained and it could be shown as a result that the particular pin operated is that pin which corresponds to the sum of the values of the perforations presented. With the perforations in each group having a value of 1:2:4:8; it will therefore be seen

that fifteen air pins for matrix case location can be operated from four perforations, since 1 plus 2 plus 4 plus 8 equals fifteen: it may be noted, however, that in the particular embodiment illustrated, only fourteen pins are operated inasmuch as this number is all that is necessary in this particular machine. 70

It will be observed in Fig. 6 that the permutating bars are placed one above the other instead of in the same horizontal plane. This is a schematic illustration, not to show the actual construction, but to make plain the relation of the slots in the members, and, consequently, the operation of the permutating mechanism. 75

In Fig. 8 I have shown a modified construction in which the permutating bars 17' are shown with selectively arranged apertures 50' instead of the slots or notches 50 as previously described. These bars are operated in the same way as the notched bars, and in their combinations of position, the apertures being in the same relation as the slots, a throughway for air under pressure entering through pipe 51 into air chamber 52 is produced whereby this air traverses a selected pipe of the group 43 and operates a corresponding air pin 150. With this construction, the apertures themselves, when placed in alignment, form directly a pneumatic connection with the air pin, and the series of valves 25 and their operating members 31 are not necessary. A group of four valves, as shown in Fig. 8, will thus operate fifteen air pins similarly to one of the groups of permutating bars already described. 90

I claim:

1. A typographic casting machine adapted to be controlled by a perforated strip the perforations of which constitute signals, said machine comprising a plurality of gaging devices and in combination therewith a plurality of signal responsive motors, permutating devices operated from said motors, and means connecting said permutating devices with said gages whereby a combination of said devices will select and cause operation of the gaging device indicated by the signal. 105

2. A typographic casting machine adapted to be controlled by a perforated strip, comprising strip advancing and clamping mechanism, a series of motors to be actuated, a series of ports under control of the strip and being less in number than the said motors, and a selector mechanism between the ports and the motors, said selector mechanism comprising a series of motors each connected with one of said ports, a series of movable members each operatively connected with one of said selector motors, said members, according as they are operated or not under control of signal components, producing by their combination a through passage-way corresponding to a selected one of the 110 120 125 130

series of motors to be actuated and means comprising a pneumatic conduit for effecting the actuation of said selected motor.

3. A typographic casting machine adapted to be controlled by a perforated strip, comprising strip advancing and clamping mechanism, a series of motors to be actuated, a series of ports under control of the strip and being less in number than the said motors, and a selector mechanism comprising a series of sliding members each connected with one of said selector motors, said members being provided with apertures selectively disposed to produce different through-ways for the various combinations of operated and non-operated members, each of said passageways corresponding to a selected one of the series of motors to be actuated and means comprising a pneumatic conduit for effecting the actuation of said selected motor.

4. A typographic casting machine comprising a series of pneumatically operated locational gages, a valve for controlling each gage, a series of ports less in number than the gages and adapted to be controlled by a perforated controller strip, a pneumatic motor in communication with each port, selector bars operated by said motors and means for operating said valves in accordance with the disposition of said bars.

5. A typographic casting machine comprising a series of pneumatically operated gages, a valve for controlling each gage, a series of ports less in number than the gages and adapted to be controlled by a perforated controller strip, a pneumatic motor in communication with each port, selector bars operated by said motors, means for operating said valves, said bars being provided with selectively disposed ways into which the valve operating means is adapted to extend to operate the valves, whereby the operation of one or more bars as controlled by the ports opens by combination a single way for the valve operating means and thus causes the operation of a single valve and its corresponding gage.

6. A typographic casting machine comprising a series of pneumatically operated gages, a valve for controlling each gage, a series of ports less in number than the gages and adapted to be controlled by a perforated controller strip, a pneumatic motor in communication with each port, selector bars operated by said motors, an operating finger for each valve, said bars being provided with selectively disposed ways into which

the operating fingers are adapted to extend to operate the valves, whereby the operation of one or more bars, as controlled by the ports, opens by combination a single through-way for a single operating finger and thus causes the operation of a single valve and its corresponding gage.

7. A pattern controlled typographic composing machine having a series of gages, one for positioning the die case in each position of adjustment, and means whereby certain of said gages respond only to the combined action of two or more signals in the pattern and other of said gages respond only to the action of individual signals in the pattern.

8. A pattern controlled typographic composing machine having a series of gages, one for positioning the die case in each position of adjustment, said machine being characterized by the provision of means whereby individual signals in the pattern control the operation of corresponding individual gages, and said signals in combination with each other control the operation of other individual gages, whereby the number of individual signals in the pattern may be reduced.

9. A typographic composing machine comprising a series of motor operated locational gages, a series of ports, means for intermittently presenting to said ports a signal in the form of one or more perforations in a controller strip, and a selector mechanism between said ports and said gages to select for operation a single gage of the series whether one or more than one signal perforation is presented to said ports.

10. In an automatic or record strip controlled type casting machine furnished with a series of gaging devices the arrangement of a number of signal responsive selective devices and control valves operated in predetermined combinations by the selective devices to determine which member or members of the gaging devices shall be actuated.

11. In an automatic or record strip controlled type casting machine, the combination with a series of positioning gages of a series of signal responsive motors adapted for separate or simultaneous operation and control devices arranged in series, each series being controlled by one of the motors and operated separately or in combination to actuate one or more of the positioning gages.

MAURITZ C. INDAHL.
